CHOCK BLOCK

Filed Sept. 15, 1928

Inventor

T. W. Griffin

By Watson E. Coleman
attorney

UNITED STATES PATENT OFFICE

THOMAS W. GRIFFIN, OF DETROIT, MICHIGAN

CHOCK BLOCK

Application filed September 15, 1928. Serial No. 306,228.

This invention relates to the class of chock blocks designed primarily for use in maintaining automobiles in fixed position during transportation.

5 The primary object of the present invention is to provide a chock block for automobiles of such character that a materially smaller body of material may be employed than is employed for chock blocks of the type 10 at present in use without sacrificing any of the advantages of the block.

Another object of the invention is to provide a wooden chock block having an improved bracing means which permits of the 15 block being made smaller than the usual types.

A still further object of the invention is to provide a wooden chock block so constructed that the same will not split or crack during 20 the drying out thereof.

The invention will be best understood from a consideration of the following detailed description taken in connection with the accompanying drawings forming part of this 25 specification, with the understanding, however, that the invention is not confined to any strict conformity with the showing of the drawings but may be changed or modified so long as such changes or modifications mark 30 no material departure from the salient features of the invention as expressed in the appended claim.

In the drawing:—

Figure 1 is an elevational view of a portion 35 of stop material showing the method of cutting the same to form two blocks of the type embodying the present invention;

Figure 2 is a side elevational view of the chock block constituting the present invention, a portion thereof being shown in section;

Figure 3 is a top plan view of the block.

Referring to the drawing in detail, the numeral 1 indicates the block embodying the 45 present invention, the same being, as shown of substantially triangular design in side elevation, having the vertical face 2, the straight or horizontal bottom face 3, and the inclined face 4 in the surface of which is 50 formed a longitudinally extending arcuate

groove or recess 5 designed to receive the tire of a motor vehicle.

The rear face 2 of the block is provided with the transverse notch 6, this notch being of gradually increasing depth from the lower 55 to the upper portion thereof, thus forming the shoulder 7.

Associated with the block is a brace arm 8, each end of which is formed to snugly fit into the notch 6 so as to provide the rearwardly extending inclined brace leg shown.

In order to lighten the weight of the block, there is formed transversely of the rear face the recess 9 and the bore 10 which is formed in the lower face or bottom as shown. The 65 bore 10 also performs another function that is, it prevents the splitting of the block as the wood from which it is made dries out.

In wooden blocks of the type at present in use, no provision is made for preventing 70 the splitting thereof and when the blocks are allowed to lie out in the weather, a considerable number split up and must be discarded. These blocks while being initially cheap to produce, therefore, become more expensive 75 because of the waste which results from the splitting described. The present block may be economically produced because of the fact that less material need be employed in their make up, the saving in the material of the 80 block proper resulting from the use of the brace leg 8 which makes it unnecessary to give a great deal of length to the block in order to make it staple. The expense attached to the use of wooden blocks as a result of the 85 splitting of the same in the manner above described is obviated by the formation of the hole or bore 10 in the bottom of the present block as the blocks dry from the center outwardly.

The blocks may be quickly formed from a length of material of the proper cross sectional design by cutting the same at right angles transversely at predetermined points, thus forming a series of rectangular blocks 95 each of which is then cut obliquely to form the inclined surfaces of a pair of blocks. The brace legs being of small form may be readily obtained from material which would otherwise go to waste.

From the foregoing description, it will be readily seen that the block herein described may be easily and quickly mounted in position and when so mounted will offer a firm brace for the motor vehicle wheel which it supports.

The block can be readily nailed in place by applying one or two nails to the front end thereof and driving one or more nails through the lower end of the brace member 8. Since the present block structure can be firmly held in place by the use of not more than four nails, it will be readily seen that the block will be more economical to use than blocks of a type present employed wherein a large number of nails must be used.

Having thus described my invention, what I claim is:—

A chock block of the character described comprising a wood body having a flat supporting face, a vertical rear face and an arcuate face designed to receive the tread of a motor vehicle tire, said body having formed in the rear face adjacent the top thereof, a substantially triangular recess of greatest depth at the upper end, and a brace leg having each end cut to conform to the shape of said recess to snugly engage therein whereby either end may be positioned therein, the other end of said brace leg being adapted for firm contact with a supporting surface to maintain the block in position.

In testimony whereof I hereunto affix my signature.
